UNITED STATES PATENT OFFICE.

ADOLPH P. KOCH, OF EFFINGHAM, ILLINOIS, ASSIGNOR OF ONE-FOURTH TO
LESLIE W. LEITH, OF SAME PLACE.

NECK-YOKE CENTER.

SPECIFICATION forming part of Letters Patent No. 416,680, dated December 3, 1889.

Application filed June 20, 1889. Serial No. 314,943. (No model.)

To all whom it may concern:

Be it known that I, ADOLPH P. KOCH, a citizen of the United States of America, residing at Effingham, in the county of Effingham and State of Illinois, have invented certain new and useful Improvements in Neck-Yoke Centers; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention relates to neck-yoke centers; and it consists in the improved construction, hereinafter described and set forth, whereby a simple and efficient arrangement is provided that will not only be cheaper and more 20 satisfactory than previous forms, but dispense entirely with the necessity for employing screws or like fastening devices for connecting the leather holdback to the metal clasp.

25 In the accompanying drawings, forming part of this specification, Figure 1 is a side view of a neck-yoke center embodying my improvements. Fig. 2 is a vertical sectional view showing the arrangement of the clamp 30 and the form of the leather sections used for the leather holdback, and Fig. 3 is a section on the line $x-x$ of Fig. 1.

The clamp A is in the form of a metal casting in a single piece, and consists of the rectangular socket a, having the end walls b inclined downwardly in the direction of each other. The said end walls b are each provided at its upper edge with a horizontally-projecting ear c, the upper face of which is 40 curved downwardly to correspond with the curved face of the neck-yoke. Said ear c is vertically perforated and is countersunk on its under side to enable the receiving-screw to bear snugly therein.

45 The leather holdback B is made up of a series of parallel thicknesses d of leather, each of which presents the outline of the holdback. The said sections d of the holdback are con-

nected rigidly together by both riveting and stitching, and the form of the holdback made thereby is such that its edges e are vertically parallel until they reach the portion C, which occupies the casting, at which point the said edges are flaring, so that said portion C will be of gradually-increasing width. The depth 55 of the leather holdback is also augmented at said portion C by the introduction of internal wedge-shaped leather sections f, located between the central thicknesses d.

By reference to Fig. 2 it will be seen that 60 the form of the leather holdback is such that its exposed portion is of such width that it can be readily dropped downward through the casting before the latter is secured to the yoke, and that the form of the portion C is such 65 that it will become tightly jammed in said casting and thus firmly connect the holdback to the casting. The tendency of all strain upon the holdback is to more firmly wedge the portion C in the casting. As will be appreciated, the absence of perforations for the 70 passage of securing-bolts to the casting avoids the weakening and wearing incident to such perforations.

The thickness d of the holdback may be 75 readily produced and renewed when necessary. The portion a of the casting is also contracted in cross-section to provide for the increased depth of the portion C, previously alluded to.

80 I claim—

The combination, in a neck-yoke center, of the metal clamp having the inwardly-inclined end walls provided with horizontal perforated ears, a holdback having a main portion of a 85 width corresponding with the narrowest portion of the clamp between the end walls, and having an enlarged portion C with flaring edges, substantially as set forth.

In testimony whereof I affix my signature 90 in presence of two witnesses.

ADOLPH P. KOCH.
